*Design No. 415.-**Nathan Lechapin**Design for Tables. Patented Sept. 30, 1857.-**Fig. 1.*Nathan Chapin, of Syracuse, N.Y.
Letters Patent, No. 415, Dated Sept. 30, 1851.

The schedule referred to in these Letters Patent and making part of the same.

To all whom it may concern:

Be it known that I, Nathan Chapin of the city of Syracuse, in the county of Onondaga & state of New York, have invented a new & beautiful design in the household table frame & drawer and I do hereby declare the following to be a full, clear & exact description of the same, reference being made to the annexed drawings making part of this specification in which,

Fig. 1, is a perspective view of one specimen of the table. The nature of my invention consists, first, in a new form of table pillars, which are turned or carved in imitation of growing vines & fixed in a pedestal at their base, standing nearly erect with — branches made to support the drawer, capital & top; with other graceful branches to make the whole appearance more elegant.

Second - The drawer & Capital are made of small pillars in form of lattice work, with openings to show their linings on all sides, having no enclosure or support except the branches of said large pillars.

Construct a round pedestal 18 inches in diameter, substantially supported by 4 feet - A. Directly over the four feet upon the pedestal, place the 4 pillars B,B, which are 2 1/2 inches in height, reclining at top 17 inches from the centre of pedestal. At the distance of 15 inches above the pedestal, place the base board of the drawer C, - 16 inches square & 5/8 in. thick, & rest the four corners of it upon the branches of the 4 pillars B,B. -

At a distance of 5 inches above this board, place another board - D, - 18 inches square and of the same thickness as the former, & rest its corners upon other branches of the said pillars, with small cleats glued upon the under surface of its margin, except one edge to receive & guide the drawer E, & keep it in its place. - 3 inches above this board, place a square frame, like a picture frame, & rest its corners upon the top of the pillars. -

This frame should be 24 inches square & 1 inch in thickness with a flaring balustrade resting upon the board last mentioned & supported by the frame at the top, forming a hollow balustrade Capital between the tops of the pillars. Upon this is placed the ordinary table top, attached to the frame by hinges at one edge so that the opposite edge can be raised to a vertical position & exposed to view a mirror which is attached to its under surface & also the inner part of the Capital.

Make a drawer E, 15 inches square & 5 inches high in form of a square balustrade box or basket work, lined with fancy cloth exposed to view through

3

the pillars of the balustrade. The Capital also is lined in the same manner with fancy cloths & shows in like manner. Turn a rim - 2 2 inches in diameter, flat at the under surface & representing a moulding at the sides & top. —

Let it encircle the four main pillars, resting upon a scroll on each, & supported by several other flaring pillars, with a like scroll upon the top —

What I claim as my invention of desire to secure by Letters Patent is the design and configuration of table pillars in the form of vines supporting by their branches the drawer & upper part of the table, with flaring scroll, balustrade pillars, supporting a rim which encircles the main pillars, together with the configuration of an ornamental, open work drawer & Capital, exposed to view on all sides — The whole combining various styles of architecture as herein before described. —
